UNITED STATES PATENT OFFICE.

ALEXANDER S. T. LAGAARD, OF MINNEAPOLIS, MINNESOTA.

DESIGN FOR A CABINET FOR A COIN-CONTROLLED GAME APPARATUS.

Application filed December 22, 1927. Serial No. 24,593 Term of patent 3½ years.

To all whom it may concern:

Be it known that I, ALEXANDER S. T. LAGAARD, a citizen of the United States, residing at Minneapolis, in the county of Hennepin and State of Minnesota, have invented a new, original, and ornamental Design for Cabinets for a Coin-Controlled Game Apparatus, of which the following is a specification, reference being had to the accompanying drawing, forming part thereof.

The figure is a perspective view of a cabinet for a coin-controlled game apparatus illustrating my new design.

I claim:

The ornamental design for a cabinet for a coin controlled game apparatus, as shown.

ALEXANDER S. T. LAGAARD.
